UNITED STATES PATENT OFFICE.

ELMER ROLAND SHARP, OF DAVENPORT, IOWA.

DESIGN FOR A VENDING-MACHINE CASING.

51,243.

Specification for Design.

Patented Sept. 4, 1917.

Application filed June 14, 1917. Serial No. 174,777. Term of patent 7 years.

To all whom it may concern:

Be it known that I, ELMER ROLAND SHARP, a citizen of the United States, residing at Davenport, in the county of Scott and State of Iowa, have invented a new and original Design for a Vending-Machine Casing, of which the following is a specification.

My invention relates to designs for vending machine casings, of that class which are intended to hold a plurality of articles for sale, in separate and adjoining compartments, in such a manner that the articles can be readily seen by the purchaser. The device shown herein is specially adapted for use in selling packages of gum by coin-operated means.

The figure in the drawing is a front elevation of a machine embodying my design, in which 1 is a hexagonal base, mounted on

a circular base-plate 2 and surmounted by a similar plate 3 of slightly less diameter than the plate 2. Mounted on the plate 3 is a hexagonal body portion in conformance with the base 1, such body portion being formed of alternate transparent plates 4 and pillars 5. Said body portion is surmounted by a circular cap 6 of less diameter than the plate 3, which forms a ledge about the body portion on all sides.

I claim:

The ornamental design for a vending machine casing, substantially as shown and described.

In testimony whereof I affix my signature in the presence of two witnesses.

ELMER ROLAND SHARP.

Witnesses:

W. N. HASKELL,
J. P. LONG.
